J. M. Cook,
Permutation Lock.
No 17,424. Patented June 2, 1857.

Fig. 1.

Fig. 2.

UNITED STATES PATENT OFFICE.

JULIUS M. COOK, OF HINSDALE, NEW YORK.

LOCK.

Specification of Letters Patent No. 17,424, dated June 2, 1857.

To all whom it may concern:

Be it known that I, JULIUS M. COOK, of Hinsdale, in the county of Cattaraugus and State of New York, have invented a new 5 and Improved Mode of Constructing Locks, which I call "Cook's Defiance Set-Lock;" and I do hereby declare that the following is a full and exact description of the said invention, reference being had to the annexed drawings and to the letters and figures of reference marked thereon.

The nature of my invention consists of the bolt or bar (a) constructed with a cavity in square form upon one side sufficiently 15 large to admit of two small wheels, (b) and (c), a set (d) and fly (e), which is made fast to a smooth plate of metal in such manner as to form a box containing the machinery, the bar and machinery sliding upon this 20 plate, as the instrument is locked or unlocked. The wheels are constructed with a notch in the side of each, so as to admit the hook upon one end of the set (d), upon the entry of which the other end of the set is 25 removed from the range of a small stud j, upon the plate f, which allows the bar to slide at pleasure. In wheel (b) is inserted a shaft, b, made firm to the wheel, this shaft being inserted through slide wheel c, at the 30 center, through a round hole, sufficiently large to allow it to turn easily upon the shaft, on which wheel is constructed a small spur near one edge of the wheel sufficiently far from the center as to come in contact 35 with that portion of fly (e) opposite the notch or swallowtail end. The spiral spring (i) is placed around the shaft (b), which presses against wheel c. The fly being passed over the shaft of the set d, is then 40 put in place as represented in letter (a), the fly being indicated by the red dots.

The bolt a, with all the fixtures is placed upon plate (f) and made fast by means of clasp (g) and (h), as represented by Figures 45 1 and 2 and letter F. The star, k, is then placed upon shaft (b), which completes the lock, to unlock which the operator places a key upon the end of shaft (d), as indicated in Fig. 1, and turns the key to the left 50 once and a half around and bringing the point on the star which protrudes directly from the side of the square of shaft (b) around to the degree on the dial opposite shaft (d). The first time the key is thus 55 turned to the left the spur on wheel c is brought into contact with that part of fly

(e), as represented by letter f, which swings the dovetail end of the fly endward, and the next time the spur passes the dovetail will be in its track, and thus the motion of 60 wheel c is stopped and wheel (b) continues its motion until the notches in both wheels exactly correspond, which occurs at the same moment the above point in the star reaches the $\frac{1}{2}$ degree to the left of the 65 crossed degree, the key is then turned to the right, so that the above point of the star, 12 degrees on the dial to the right of the degree indicated by the dash or cross at the top. Also indicated by the little dot (.) on 70 the dial No. 1. At this point the notches in the wheels are brought opposite the hook (n) on the set, the key is then removed and placed upon shaft (d) and turned to the left, by which means the hook n enters the 75 notches in the wheels and the other end of the set is brought out of line with the stud upon the plate and allows the bolt to slide at pleasure.

To lock the machine the set is removed 80 from the notches in the wheels and the key placed upon shaft (b) and turned once and a half at least to the left, and the notches in the wheels become displaced again.

Fig. 1 represents a front view of my lock. 85 Fig. 2, consists of a side view of my lock.

Letter a, represents a separate view of inner portion of the bolt, wheels, fly and set, as appears when unlocked.

B is a separate view of the wheel b, and 90 shaft.

Letter c, is a view of slide wheel with spur p.

Letter d is a separate view of the set and shaft. 95

Letter e, as indicated on f by the red dotted lines, is a separate view of the fly.

Letter f is a view of the plate in connection with machinery in a locked condition. Stud j, and the hook M of the set are in 100 conjunction.

Letter G, is a separate view of the clasp by which means the bolt a is attached to plate f by means of nuts and screws.

Letter h is a separate view of the clasp 105 at the rear end of bolt a, and by means of which it is attached to plate f, by nuts and screws.

Letter i is a separate view of the spiral spring.

Letter j, as indicated upon plate f, is a 110 view of the stud upon the plate.

Letter *k*, is a separate view of the star.
Letter *l* in plate *f* is a view of an opening
in the plate to admit a clasp sufficiently
strong through which the bolt is to pass
5 when locked.

m is a view of the hook, on the set.

n, is a view of the hook which passes into
the notches in the wheels.

Letter *o* is a view of the notch in the
10 wheels.

Letter *p*, is a view of the spur on wheel *c*.

Letter *q* presents a view of thumb piece
upon the bolt *a*.

What I claim as my invention, and de-
sire to secure by Letters Patent, is:

15

The set, arranged and operating in con-
nection with the wheels, fly and shaft as
herein described:

JULIUS M. COOK.
